DRAWING ROLLS FOR SPINNING MACHINES

William Beswick, Birmingham, Ala.

Application September 4, 1942, Serial No. 457,277

6 Claims. (Cl. 19—130)

My invention relates to drawing rolls for attenuating machines in textile mills, such as the drawing, slubbing, intermediate, speeder and spinning frames.

One of the objects of this invention is to provide drawing rolls for such attenuating machines in which the pressure on the roving is exerted over a relatively wide area, whereby the fibers are evenly drawn and not pulled out of turn.

A further object of my invention is to provide drawing rolls for use in attenuating machines in which the rolls cooperate with concentric troughs in closely spaced relation to the rolls, and the roving is caused to pass between the rolls and the troughs, thereby providing a much longer and evener draft than is possible where roving is caused to travel between cooperating rolls.

A still further object of my invention is to provide an apparatus of the character designated in which a plurality of drawing rolls are caused to cooperate with closely adjacent concentric troughs providing ridges between the adjacent troughs over which the roving is drawn and in which the proper pressure between the rolls and the troughs may be obtained by adjustment of the troughs with relation to their cooperating rolls.

As is well known in the art to which my invention relates, the drawing of roving in textile mills is usually accomplished by a plurality of pairs of drawing rolls arranged in series between which the roving passes with progressively increasing speeds of rotation for the successive pairs of rolls. Each pair of rolls has a relatively firm grip on the roving and in order to accomplish the draft, it is necessary for the several pairs of rolls to be spaced apart a distance at least slightly greater than the length of the fibers making up the roving. This results in an uneven drawing, because the fibers are always drawn at the weakest point in the roving, and in spite of careful attention to operation, uneven places in the yarn can be detected.

In accordance with my invention, this difficulty is overcome by effecting the draft through a series of single drawing rolls which cooperate with concentric troughs, forming ridges between the rolls, and which may be spaced closely adjacent, or much closer than the length of staple or fiber from which the yarn is being spun. By this means, none of the fibers can be drawn out of turn, but all are acted upon evenly by the rolls. It is contemplated by my invention that the successive rolls will have progressively increasing

speeds as in attenuating apparatus heretofore known to the art, whereby the desired draft may be obtained. The adjustment of the troughs with relation to the rolls permits an even pressure on the roving which provides an even draft of the fibers. It is further contemplated that the rolls may be spaced apart at varying distances to accommodate various lengths of fibers. The troughs may be of any suitable material, such as machined metal, pressed metal, porcelain, glass or plastic material. The drawing rolls are preferably fluted metal in order to obtain a better grip on the fibers.

Apparatus embodying features of my invention is illustrated in the accompanying drawings forming a part of this application, in which

Fig. 1 is a front elevational view of a drawing roll assembly made in accordance with my invention;

Fig. 2 is an end view of the same;

Fig. 3 is a sectional view taken along the line III—III of Fig. 1;

Fig. 4 is a detail sectional view of one form of cooperating trough employed with my invention;

Fig. 5 is a view similar to Fig. 4, but showing spacer blocks interposed between certain of the troughs; and

Figs. 6 and 7 are views showing different forms of trough elements.

Referring to the drawings, I show roll stands 10 and 11, in which the rolls are supported. Spanning the stands 10 and 11, and secured thereto by any suitable means, is a bottom plate 12. Front bearing supports 13 and 14 are slidably mounted on the stands 10 and 11 respectively, and rear bearing supports 16 (only one of which is shown) are mounted on the rear of the roll stands. Mounted on the bearing support 14 are intermediate bearings 17, 18 and 19, duplicate bearings (not shown) being provided on the opposite stand 10. The bearing supports 14, 17, 18 and 19 are slidable with respect to each other and are held in position by a bolt 21. The distances between the rolls may thus be adjusted in a manner well understood. Likewise, the bearing support 16 is slidable with respect to the roll stand and is held in place by an adjusting bolt 22.

Mounted in the bearing support 14 is a bottom fluted metal roll 23, which preferably cooperates with an upper covered roll 24, although a fluted top roll may be employed, as is well understood. Likewise, at the back of the assembly in bearing support 16 a bottom fluted metal roll 26 and a covered top roll 27 are employed. These rolls

50

may have any suitable covering known to the art. The top rolls 24 and 27 may be weighted by means of a saddle 28, bridle 29, and weighted lever arm 31.

Interposed between the front and back pairs of rolls already described are three intermediate single rolls 32, 33, and 34, which are preferably made of metal and fluted. The roll 32 cooperates with a concentric trough 36, the roll 33 with a concentric trough 37, and the roll 34 with a concentric trough 38. In the embodiment shown in Fig. 3, the troughs are formed in separate blocks of metal 39, 41 and 42 respectively, which are machined out and polished. They are held in position by means of end straps 43 (see Fig. 4), each of which is provided with a longitudinal slot 44 to receive clamping screws 46. The troughs are supported and held in proper adjusted positions with respect to the rolls by means of adjusting screws 41, 48 and 49, which pass through the bottom plate 42. Each of said screws is provided with nuts 51 and 52 to hold it in its adjusted position. It will be noted that where the blocks 39, 41 and 42 join, they form ridges, such as 53 and 54, between them. It will also be noted that each trough defines, in cross section, slightly less than a semi-circle, so that the centers of the rolls are above the sides of the troughs. It will further be noted, by reference to Fig. 3, that the block 42 is so shaped as to provide a considerable distance, defined by a flat surface 56, between the back rolls 26 and 27 and the first intermediate roll 34. This distance is to provide a "break draft" or slight loosening of the twist in the roving, and is preferably made slightly greater than the average length of staple or fiber being spun. An opening 55 is provided through the block 41 between sections of the roll 33 to provide a passage for the bridle 29.

From the foregoing the operation of the apparatus so far described will be apparent. The roving indicated by the letter S enters between the back rolls 26 and 27 through the trumpet indicated at 57. It passes over the surface 56, which permits the fibers to loosen slightly before the drawing begins. The roving then passes successively under the fluted rolls 34, 33, and 32, across the troughs 38, 37, and 36, in the order named, and out between the front rolls 23 and 24. It will be understood that the rolls are driven at progressively increasing speeds from back to front in a manner well understood and which is not shown in the drawing. For example, the ratio of speed of the roll 34 to rolls 26 and 27 will be the usual break draft of 1.15 to 1.25. The ratio of speed of roll 33 to 34 may be from 3.00 to 4.00; and the ratio of the speed of roll 32 to 33 may be from 5.00 to 6.00. The ratio of the speed of the front pair of rolls 23 and 24 to roll 32 would be approximately 1.10, as the drawing has already been completed by the time the roving leaves the front intermediate roll 32. It will be seen that by means of my invention, the roving is contacted by each of the fluted intermediate rolls for a distance almost equal to one-half the circumference of the roll, and partial drawing may occur for the entire distance the roving is being pulled across the trough. It appears, however, that the principal part of the drawing occurs as the roving is passing over the ridges 53 and 54. Placing the centers of the intermediate rolls above the ridges 53 and 54 and surface 56 causes the roving to enter underneath the rolls and prevents any

difficulty in threading the roving through the rolls.

Referring to Fig. 5, I show the blocks 39, 41 and 42 spaced apart by means of spacer blocks 61 and 62. By the provision of such spacer blocks, and by the adjustment of the positions of the bearing supports 17, 18 and 19, any desired spacing between the intermediate rolls 32, 33 and 34 may be obtained.

In Fig. 6 I show a form of my invention in which the troughs 36, 37 and 38 are formed in a molded block 63, which may be made of any moldable material, such, for example, as glass, resin, porcelain, or of many other materials which will suggest themselves to those skilled in the art. The molded block thus formed may be secured to a suitable backing 64 by screws 66.

A still further form of my invention is shown in Fig. 7, in which the troughs 36, 37 and 38 are formed of pressed metal and secured to a suitable backing 67 by screws 68.

From the foregoing it will be apparent that I have devised an improved attenuating apparatus for textile mills which is simple of design and operation, and by means of which an improved drawing of the roving may be effected.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are specifically set forth in the appended claims.

What I claim is:

1. In a textile attenuating apparatus, the combination of a plurality of spaced drawing rolls driven at progressively increasing speeds, troughs in which parts of the rolls are adapted to rotate in spaced relation thereto and defining between the troughs ridges over which roving is adapted to be drawn, and means to pass roving to be drawn in series between the rolls and the troughs transversely of the ridges.

2. In a textile attenuating apparatus, the combination of a plurality of spaced drawing rolls driven at progressively increasing speeds, troughs in which parts of the rolls are adapted to rotate in spaced relation thereto, and defining between the troughs ridges over which roving is adapted to be drawn, means to pass roving to be drawn in series between the rolls and the troughs transversely of the ridges, and means to adjust the position of the troughs toward and from the rolls.

3. In a textile attenuating apparatus, a front pair of rolls, a back pair of rolls, a plurality of single intermediate rolls interposed between the front and back rolls and driven at progressively increasing speeds from back to front, troughs cooperating with the intermediate rolls and providing ridges between adjacent rolls, and means to pass roving transversely between the intermediate rolls and the troughs to effect a drawing of the roving.

4. Apparatus as defined in claim 3, in which the back pair of rolls is spaced from the next adjacent single roll a distance greater than the length of fiber from which the roving is being spun to permit a break draft between said rolls.

5. Apparatus as defined in claim 3, in which the troughs are formed in separate blocks and means are provided to space the blocks laterally with respect to each other, together with spacer blocks filling the intervening spaces between said

separate blocks and secured in place with respect thereto.

6. In a textile attenuating apparatus, a back pair of rolls, a front pair of rolls, a plurality of single intermediate rolls interposed between the front and back rolls, said rolls being driven at progressively increasing speeds from back to front, troughs cooperating with the intermediate rolls and providing ridges between adjacent rolls,

means to pass roving through the apparatus from back to front and between the intermediate rolls and the troughs to effect a drawing of the roving, means to adjust the positions of the troughs toward and away from the rolls, and means to adjust the spacing of the troughs together with their cooperating rolls with respect to each other.

WILLIAM BESWICK.
